UNITED STATES PATENT OFFICE.

ABRAHAM FINN, OF ELIZABETH, NEW JERSEY.

PLASTERING DEVICE.

Application filed August 1, 1924. Serial No. 729,580.

To all whom it may concern:

Be it known that I, ABRAHAM FINN, a citizen of Russia, residing at Elizabeth, in the county of Union and State of New Jersey, have invented new and useful Improvements in Plastering Devices, of which the following is a specification.

This invention relates to improvements in plastering devices.

10 The principal object of the invention is the provision of a device for use in plastering the ceiling and walls of a room by applying the plaster in sections, by first placing the plaster upon the device and then lifting the same to the spot where the plaster is to be secured. If desired, the device may be constructed of a size large enough to permit the entire surface to be plastered in a minimum number of operations.

20 Another object of the invention is to provide a device which may be operated by a single person and which eliminates the objection of applying the plaster to the ceiling of a room by the use of a trowel or other implement which is a very tiresome process.

A further object is to provide a plastering device which is simple in construction, cheap of manufacture and easy of operation.

With these and other objects in view, the 30 invention resides in certain novel construction and combination and arrangement of parts, the essential features of which are hereinafter fully described, are particularly pointed out in the appended claims, and are 35 illustrated in the accompanying drawings in which:—

Figure 1 is a perspective view of my improved plastering device of the type for applying the finishing coat of plaster.

40 Figure 2 is a top plan view of the same.

Figure 3 is a sectional view on the line 3—3 of Figure 2.

Figure 4 is an enlarged detail sectional view on the line 4—4 of Figure 2.

45 Figure 5 is an enlarged detail sectional view on the line 5—5 of Figure 2.

Figure 6 is a diagrammatic view showing the manner in which the plaster is applied.

50 Figure 7 is a modified form showing the type of device used for applying the rough coat of plaster.

Figure 8 is a sectional view on the line 8—8 of Figure 7.

55 Referring more particularly to the drawings, the reference character A designates

my invention in its entirety, and which includes a board or platform 10, to the underside of which is secured handles 11 at opposite ends thereof. The handles 11 are of such construction as to serve as legs for supporting the device when the same is resting upon the ground or other support. The platform 10 in the present instance is shown as square in plan, but may be of any suitable shape such as triangular, and completely encircling the edges of the platform is a movable wall 12. The wall 12 includes two high sides 12^a and two lower sides 12^b and is yieldingly supported at the corners by a means 13, and which means includes a depending bracket 14 provided with a seat 15 for receiving the one end of a spring 16. The wall 12 rests upon the other end of the springs to hold the wall in a raised position above the side edges of the platform to prevent the plaster which is placed thereon from spreading over the side edges. Depending from opposite sides of the walls are handles 17 which are pivotally connected to the wall and which are arranged adjacent the handles 11 of the platform. From the description thus far, it will be seen that the handles 11 and 17 may be simultaneously grasped by the hands, and the handle 17 depressed so as to move the wall 12 downward below the surface of the platform against the tension of the springs 16, and upon release of the handle 17 the wall will move back to its normal position.

As hereinbefore mentioned, the plaster is applied in sections as shown diagrammatically in Figure 6, and when so applying the same, it has been found necessary to provide a guide means 18 for co-action with the structure which receives the plaster, for holding the device in a steady position so that the section may be applied evenly to the sections already applied, and for gauging the thickness of the plaster when applying the same. The means 18 comprises an angular rail 19 which surrounds two sides of the platform and is spaced from the wall 12 as clearly shown in Figure 2. The rail 19 is adjustably supported with relation to the platform by a bracket 20 secured to certain of the brackets 14 and which brackets have spaced ears 21 provided with slots 22 opening on opposite sides of the ears. Extending through the slots 22 of each bracket is a screw 23, having 110

- a knurled head 24 at one end and a head 25 at its other end said last head being formed with a slot or kerf 26 in the top face thereof. The rail 19 rests in the slots of the respective screws and is removably held therein by set screws 27. A lock nut 28 is threaded to each screw between the spaced ears and co-acts with the lower ear for holding the same in adjusted position after the desired adjustment of the rail is obtained by rotating the knurled head 24. By forming slots in the recesses of the brackets, it is possible to remove the screw should it be desired to collapse the structure.
- 15 Mounted adjacent one corner of the platform is an adjusting member 29, which is threaded in the platform and is provided with a manipulating head 30. The member is adjusted to the level of the guide rail 10 and co-acts with the same for evenly applying the plaster.
- It will be understood that in practice, plaster is spread upon the platform 10, and the device lifted to the desired spot by 25 grasping the handles 11, after which the handles 17 are depressed and pressure applied to the device until the rail 19 is flat against the structure which receives the plaster. The plaster will then adhere to 30 the previous coat, as it will be understood that the device shown in Figures 1 to 5 inclusive is employed for applying the finishing coat, after which the device is lowered and the operation repeated.
- 35 One of the side walls is provided with cut-away portions 31 to permit the excess plaster to flow from the platform when applying the same, and a trough 32 encircles the walls to receive the overflow. The lower 40 sides 12^b of the walls are provided with pins 33 for aligning the section to be applied with the portion of the ceiling already covered.
- In order to prevent the plaster from sticking 45 to the platform, I provide a strip of water proof material 34 which is first placed upon the platform prior to filling the same with plaster, and the same is held in position thereon by pins 35. The strip of material 50 will leave the platform when the plaster is applied, but may be removed from the ceiling after the same is thoroughly dried.
- In the form shown in Figures 7 and 8 for 55 applying the first coat of plaster or for plastering walls which necessitates the tilting of the device, I provide the platform with spring fingers 36 which project slightly above the upper surface of the platform to 60 prevent the plaster from slipping from the platform during the application of the same. In other words, the fingers serve to reinforce the congealed mass. The walls 12' in this form are of the same height and the 65 pins 33 are dispensed with. It is unneces-

sary to use the strip 34 in the device as the strip is only necessary to give the plaster a finished appearance.

While I have described what I deem to be the most desirable embodiment of my invention, it is obvious that many of the details may be varied without in any way departing from the spirit of my invention, and I therefore do not limit myself to the exact details of construction herein set forth 75 nor to anything less than the whole of my invention limited only by the appended claims.

What is claimed as new is:—

1. A device of the class described comprising a platform, a wall encircling said platform, manually operable means for moving said wall below the surface of said platform, and automatic means for returning said wall to normal position upon the release of said manually operable means. 80

2. A device of the class described comprising a platform, a wall encircling said platform, manually operable means for moving said wall below the surface of said platform, automatic means for returning said wall to normal position upon the release of said manually operable means, and a guide rail spaced from said wall. 90

3. A device of the class described comprising a platform, a wall encircling said platform, manually operable means for moving said wall below the surface of said platform, automatic means for returning said wall to normal position upon the release of said manually operable means, a guide rail spaced from said wall, and means for adjusting said guide rail with respect to said platform. 95

4. A device of the class described comprising a platform, handles at opposite sides of said platform, a wall encircling said platform and yieldingly mounted with respect to said platform, and handles on opposite sides of said wall and depending adjacent 100 said first handles, substantially as and for the purpose specified. 105

5. A device of the class described comprising a platform, handles at opposite ends of said platform, a wall encircling said platform and yieldingly mounted with respect to said platform, handles on opposite sides of said wall and depending adjacent 115 said first handles, and a guide rail spaced from said wall, and means for adjustably supporting said guide rail with respect to said platform. 120

6. A device of the class described comprising a platform, handles at opposite ends of said platform, a wall encircling said platform and yieldingly mounted with respect to said platform, handles on opposite sides of said wall and depending adjacent said first handles, a guide rail spaced from said 125 wall, means for adjustably supporting said 130

guide rail with respect to said platform, and yieldable fingers arranged along the upper surface of said platform.

7. A device of the class described comprising a platform, handles at opposite ends of said platform, a wall encircling said platform and yieldingly mounted with respect to said platform, handles on opposite sides of said wall and depending adjacent said first handles, a guide rail spaced from said wall, means for adjustably supporting said guide rail with respect to said platform, and a strip of material covering the upper surface of said platform.
8. A device of the class described comprising a platform, a wall encircling said platform, manually operable means for

moving said wall below the surface of said platform, and means for receiving the overflow from said platform.

9. A device of the class described comprising a platform, handles at opposite ends of said platform, a wall encircling said platform and yieldingly mounted with respect to said platform, handles on opposite sides of said wall and depending adjacent said first handles, a guide rail spaced from said wall, means for adjustably supporting said guide rail with respect to said platform, and a trough encircling said wall for receiving the overflow from said platform.

In testimony whereof I have affixed my signature.

ABRAHAM FINN.
